UNITED STATES PATENT OFFICE.

ERNEST E. HALL, OF NEW ELTHAM, LONDON, ENGLAND.

ZIGZAG-COURSE CONTROL.

1,253,816.

Specification of Letters Patent. Patented Jan. 15, 1918.

Application filed July 11, 1917. Serial No. 180,001.

To all whom it may concern:

Be it known that I, ERNEST E. HALL, a subject of the King of Great Britain, and a resident of New Eltham, London, S. E., England, have invented a new and Improved Zigzag-Course Control, of which the following is a full, clear, and exact description.

This invention relates to course controls and particularly to an improved construction whereby the steersman may instantly shift the direction of travel of a ship without an audible order from the officer in charge.

The object in view is to provide an improved construction adapted to be placed near the steersman of a ship whereby the ship may be steered on a specified course and turned exactly at the right time on the different courses.

Another object of the invention is to provide a device which may be adjusted and the plan or course varied as often as necessary and yet maintain the ship near its true course.

A still further object of the invention is to provide an improved device including chart members which will insure the correct steering of the ship in a zig-zag course and bring the ship back to a true course at stated intervals.

In the accompanying drawings:

Figure 1 is a diagram showing my improved zig-zag course control device.

Fig. 2 is a longitudinal horizontal section through a course control formed according to my invention.

Fig. 3 is a detail perspective view of one of the contact bars shown in Fig. 2.

Fig. 4 is a diagram showing a plotted course.

Referring to the accompanying drawings by numerals, 1 is a board or support of any kind, to which holders 2 and 3 are secured, these holders being provided so as to accommodate the slips 4, 5, 6 and 7, respectively, said slips containing information herein-after fully described. Arranged adjacent the holders 2 and 3 are rows of lamps 8 and 9 connected on one side to the common return wire 10 and on the opposite side to the respective sockets 11. The common return wire 10 is connected to a bell or other sounding device 12, which in turn is connected to a

battery or source of current 13, said battery or source of current being connected or grounded on the clock 14 so as to maintain the minute hand 15 continually in electrical communication with the source of current. The clock 14 may be any suitable make of clock and may be clamped to board 1 in any desired manner.

A ring 16 is clamped by suitable fastening means to the board 1, said ring being spaced therefrom by supporting legs 17 so as not to come in contact with the clock. Ring 16 is provided with a number of arc-shaped slots 18 for accommodating the various movable contacts 19 shown in detail in Fig. 3. These contacts are clamped by suitable bolts 20 to the ring 16 and extend to a position above the outer end of the minute hand 15 so that when a metallic pin 21 is fitted into the apertures 22 and 23 arranged in each of the contact members, it is in the path of movement of the hand so that when the hand reaches the pin the circuit of the bell 12 will be closed provided the pin 21 is connected by the wire 24 to one of the sockets 11. This is preferably done by having a pin 25 connected with wire 24 and formed of such a size as to fit the socket 11, as shown in Fig. 1.

In the drawing the parts are arranged and the slips 4 and 5 are provided with such information as to produce an hour's plotting. During the use of the device, as soon as the minute hand strikes the pin 21 the bell 12 is sounded and the course of the ship is changed by the steersman. The officer in charge also immediately removes plug or pin 21 from the position shown in Fig. 1 to the next contact, which in this instance is arranged between seven o'clock and eight o'clock. Pin 25 is also removed and placed in the next lower socket. When the hand 15 reaches the pin 21 again the ship's course is again changed and the pins 21 and 25 are also changed to the next set of contacts or sockets. This method of setting forward the pins is carried out until the bell has rung after the pin 25 has been placed in the lowest socket 11. Another set of slips is then provided in the holder 2 and the arrangement of the pins repeated. If desired, the slips 6 and 7 in holder 3 could be utilized for the second period, one period being preferably one hour, though other periods may

be used. In Fig. 1 are shown the slips 4 and 5 with figures and other information thereon corresponding to the course plotted in the diagram shown in Fig. 4, and when correctly followed will consume one hour in time and will cause the ship to leave the true course at the beginning of the hour and to again reach the true course at the end of the hour.

10 As the parts are arranged in Fig. 1 a course is disclosed as shown by the diagram in Fig. 4. On the slip 5 will be seen orders to the steersman and the number of minutes occupied on each of the sections of the zig-zag course, while on slip 4 will be seen proper information indicating the direction of travel of the ship. As shown in the diagram and as indicated on the slips 4 and 5 in Fig. 1, the ship leaves the true course indicated by the line 26 in Fig. 4 and follows a course to port for seven and one-half minutes, as indicated at 27, said course being 30° W. of N. as indicated on slip 4. At the end of the seven and one-half minutes 25 the hand 15 moves to a position in contact with the pin 21 as above described so that the bell 12 will be sounded. The steersman then immediately swings the ship around to the course 28, which is 45° starboard, as indicated on slip 5. This course is held for ten minutes or until the hand 15 strikes the pin 21 again so as to sound the bell 12. The steersman then immediately turns the ship to a true northern course, which is parallel 30 to the true course, and maintains the ship in its new course for seven and one-half minutes. As soon as the bell rings the steersman again changes the course, as shown at 29, and maintains it at the course 35 29 for twelve and one-half minutes.

40 A particular zig-zag course is shown plotted in Fig. 4 for one hour, but the steersman does not see this course though the ship will follow this course when the steersman follows the instructions on sheet 45 5, and the officer in charge will know the exact position of the ship at all times by glancing at the plotted course and at the information on slip 4, which gives the true 50 direction of movement of the ship. At the end of the hour the officer in charge could have the same zig-zag course repeated or could substitute any other desired plotted course, as for instance, a reverse of the first 55 course. One hour's zig-zag course has been shown but it will be understood that a half hour's course, a two hours' course or a course of any desired length of time may be provided and arranged in both of the 60 holders 2 and 3. It will also be understood that the contacts adjacent the clock will be adjusted to suit the information on the respective slips. The zig-zag produced by this method of shifting the course of the

65 ship is scientifically arranged so that for the entire time occupied in passing from one point to the other the true course is always known and the true position of the ship is always known in respect to said course. This is necessary in view of the danger of 70 striking sand bars or going ashore when nearing land. The zig-zag course produced is intended to confuse the officers of a submarine when attempting to fire a torpedo at a merchant ship or other ship. The changing of the course every few minutes will prevent the proper calculation in order to cause the torpedo to strike, but if the course was not properly laid out in respect to the true course the ship might accidentally go 75 80 ashore.

What I claim is:

1. In a device for causing the steersman of a ship to properly steer the ship in a zig-zag course so as to leave the true course at 85 one point and come back to said true course after a predetermined interval, an order slip provided with orders arranged in a certain sequence, an information slip provided with information indicating the direction of 90 movement of the ship, an alarm, means for causing said alarm to operate, a clock for causing said means to operate said alarm, and a manually operated switching mechanism formed so as to be shifted successively 95 in the same sequence as the arrangement of the orders on said slip whereby the steersman of the ship may change the course immediately upon the sounding of said signal and thereby maintain the true zig-zag 100 course from one point on the true course to a second point on the true course.

2. In a device of the character described, a support, a clock arranged on said support provided with a minute hand, a ring arranged near said clock, a plurality of adjustable contacts arranged on said ring, said contacts being so positioned that said minute hand will pass near the same during its movement, an order sheet provided with 110 different information thereon, an electrical socket arranged opposite each of said articles of information, an alarm, means for connecting said sockets with said alarm, means for connecting said alarm with said minute hand, said last mentioned means including a source of current, and an electrical connector adapted to have one end in electrical contact with any of said sockets and the opposite end in contact with any of said 115 contacts.

3. In a device of the character described, a support, a clock arranged on said support, a ring connected with said support adjacent said clock, a plurality of spaced contacts arranged on said ring, a pin adapted to be brought into engagement with any of said contacts and to project into the 120 125

path of movement of the minute hand of said clock, a holder arranged near the clock, an order slip provided with spaced orders arranged in said holder, a signal member, a 5 socket arranged opposite each of said orders, electrical means connecting said sockets with said signal member, said hand and a

source of current, and means adapted to be positioned in any of said sockets and brought into contact with said pin, where- 10 by when said hand strikes said pin said signal will be operated.

ERNEST E. HALL.
